UNITED STATES PATENT OFFICE.

CALVIN R. GREEN AND DAVID R. GREEN, OF RISING SUN, INDIANA.

TELEPHONE SYSTEM.

No. 823,215.

Specification of Letters Patent

Patented June 12, 1906.

Application filed August 24, 1905. Serial No. 275,645.

To all whom it may concern:

Be it known that we, CALVIN R. GREEN and DAVID R. GREEN, citizens of the United States, residing at Rising Sun, in the county 5 of Ohio and State of Indiana, have invented certain new and useful Improvements in Telephone Systems, of which the following is a specification.

This invention has relation to electric 10 means for effecting communication between different points, such as any subscriber on a party-line telephone-circuit and central, or vice versa.

In accordance with this invention separate 15 electromagnets are arranged in the main and party lines, the main-line electromagnet being polarized by a permanent magnet and adapted to be energized from central or exchange, either for selective or cutting of the 20 party-line or branch into circuit, or both. The party or branch line electromagnet enables either the subscriber or the operator at central to ring off or cut the instrument out of circuit when through talking and also provides 25 means whereby the subscriber may call central or exchange, so as to be placed in communication with the party with whom it is desired to talk.

For a full description of the invention and 30 the merits thereof and also to acquire a knowledge of the details of construction of the means for effecting the result reference is to be had to the following description and accompanying drawings.

While the invention may be adapted to 35 different forms and conditions by changes in the structure and minor details without departing from the spirit or essential features thereof, still the preferred embodiment is 40 shown in the accompanying drawings, in which—

Figure 1 is a perspective view of an instrument embodying the invention. Fig. 2 is a diagrammatical view showing the circuits in 45 normal position. Fig. 3 is a view similar to Fig. 2, showing the circuits when the main and party lines are in communication. Fig. 4 is a view similar to Fig. 2, showing the direction of the circuit when ringing off or closing 50 the resetting-circuit.

Corresponding and like parts are referred to in the following description and indicated in all the views of the drawings by the same reference characters.

55 The instrument comprises a base 1, a permanent magnet 2, a multiple electromagnet

3, party-line electromagnet 4, a circuit-controller 5, and stop and trip devices coöperating with the circuit-controller and with said electromagnets. The multiple electromagnet 3 is included in the main line, and its component parts are arranged upon opposite sides of the permanent magnet 2, so as to be polarized thereby and admit of selecting the circuit according to existing conditions. The 60 electromagnet 4 is included in the party, subscriber's, or branch line and is utilized by both the subscriber and central for ringing off or returning the parts to normal position. The circuit-controller 5 is normally acted upon by a 65 force which when unrestrained imparts movement thereto. The mechanical construction of the circuit-controller and the manner of supplying actuating force thereto are unimportant within the purview of the invention 70 so long as said circuit-controller when released automatically moves to effect making or breaking of the circuits in the manner presently to be described. As illustrated, the circuit-controller is of circular form and receives 75 a rotary movement, a weight 6 being the means for imparting movement thereto. The circuit-controller may have any desired form and receive movement in any direction so long as the circuits are made and broken in 80 a way to effect the intent of this invention.

A lever 7, fulcrumed at 8 between the elements of the multiple electromagnet 3, is provided with armatures 9 for coöperation with the respective electromagnets. A detent-lever 10, fulcrumed between its ends to a standard 11, secured to the base 1, is provided at its outer end with a hook 12 and has its inner end underlapping the lever 7, so as to be depressed thereby when either one of the electromagnets 3 or 4 is energized. The purpose 90 of the detent-lever 10 is to coöperate with the circuit-controller and hold it in the required position against the force normally acting thereon to effect movement thereof. Two 95 shoulders or stops 13 are provided on the circuit-controller to be engaged by the hook 12 to positively hold the circuit-controller against the force normally tending to effect movement thereof. The circuit-controller 100 has two lifting or cam portions 14 and 15, the portion 14 serving to move all of the shiftable contacts and the part 15 acting to move one only of said shiftable contacts, whereby either party may ring off or effect a resetting of the 105 instrument when required.

Referring to the diagrams 2, 3, and 4, the

central or exchange is indicated at A and the subscriber at B. The main line is represented by the reference-numerals 16 and 17, the wire 16 terminating within the fixed contact 18, and the wire 17 being in electrical connection with the blade 19, carrying the movable contact 20. The branch or party line is indicated at 21 and 22, the wire 21 being in communication with the blade 23, carrying the movable contact 24, and the wire 22 being electrically connected with the fixed contact 25. One terminal of the multiple electromagnet 3 is grounded by the wire 26, whereas the other terminal is connected by wire 27 with the fixed contact 28. One terminal of the electromagnet 4 is grounded by means of wire 29 and the other terminal is connected by wire 30 with blade 31, carrying the multiple contact 32. A lead-wire 33 connects the branch wire 22 with the fixed contact 34, and a companion lead-wire 35 connects the branch wire 21 with the fixed contact 36. The subscriber for each party on a circuit is provided with an instrument comprising a telephone 37, a magneto 38, and switches 39 and 40. Fig. 2 represents the normal arrangement of the parts—that is, with the movable or shiftable contacts 24, 20, and 32 electrically disconnected from the respective contacts 18, 25, and 36 and with the contacts 20 and 32 electrically connected with, respectively, the contacts 28 and 34. Suppose it be required to call central by any subscriber or party-line or branch in order to be placed in communication with the party desired to talk with. The subscriber throws switch 40 into the dotted-line position indicated in Fig. 2 or the full-line position shown in Fig. 3 and rings magneto 38. The circuit thus established is as follows: beginning at ground 41, through wire 42, to switch 40, wire 43, magneto 38, wire 44, switch 39, wire 45, line 22, wire 33, contacts 34 and 32, blade 31, wire 30, electromagnet 4, wire 29, to ground 46. On the other hand, suppose central should call a subscriber, the circuit is as follows: beginning at ground 47, through instrument 48^a, wire 17, blade 19, contacts 20 and 28, wire 27, electromagnet 3, wire 26, to ground 48. Upon establishing either of the aforesaid circuits the lever 7 is actuated and effects a movement of the detent-lever 10, whereby the circuit-controller 5 is released and moving forward brings the cam portion 14 in engagement with the blades 31, 19, and 23, with the result that the contacts 20 and 24 are caused to make electrical connection with the respective contacts 25 and 18, and the contacts 32 and 20 are electrically disconnected from the respective contacts 34 and 28. This is indicated most clearly in Fig. 3. The contact 32 in the initial movement of the circuit-controller, while electrically disconnected from the contact 34, does not make electrical connection with the contact 36, as indicated in

Fig. 3. In the initial movement of the circuit-controller the talking-circuits are established as indicated in Fig. 3. As the circuit-controller reaches the limit of its movement the cam portion 15 comes in contact with its blade 31 and moves it so as to bring the contact 32 into electrical connection with the contact 36, as shown most clearly in Fig. 4, thereby enabling either party to effect a resetting of the instruments by ringing off. After the parties are through talking and it is required to return the circuit to normal position the subscriber throws the switch 39, as shown in Fig. 4, and the circuit thus established is as follows: from ground 41, through wire 42, switch 39, wire 44, magneto 38, wire 43, switch 40, wire 49, line-wire 21, wire 35, contacts 36 and 32, blade 31, wire 30, electromagnet 4, wire 29, to ground 46. Upon making the resetting-circuit the lever 7 is a second time actuated and trips the detent-lever 10 to release the circuit-controller 5, which moves a distance to complete the rotation and return to normal position. Suppose central or exchange should ring off. In this event the circuit would be as follows: from ground through wire 16, contacts 18 and 24, blade 23, wire 21, wire 35, contacts 36 and 32, blade 31, wire 30, electromagnet 4, wire 29, to ground 46. In the practical operation of the invention each subscriber of a party-line is provided with an instrument constructed substantially as herein set forth, thereby enabling the operator at central to call any subscriber without attracting attention of others on the same line and at the same time providing means whereby any subscriber may call central, so as to be placed in communication with any other party in the same circuit or on a different line with whom communication is desired to be had. In the installation of a system of telephoning in accordance with this invention each party included in a circuit is provided with an instrument substantially as herein disclosed, the same being connected so as to provide the several circuits whereby the different operations specifically recited may be attained.

Having thus described the invention, what is claimed as new is—

1. In a telephone system, the combination of main and party lines, an electromagnet included in the main line, a separate electromagnet arranged to be included in either the main or the party line, a series of circuit-closers, a circuit-controller normally acted upon by a force, a detent for normally holding said circuit-controller in restraint against the force normally tending to move the same, an electrically-controlled releasing mechanism for liberating the circuit-controller to permit automatic actuation thereof, substantially as set forth.
2. In a telephone system, the combination

of main and party lines, circuit-closers therefor including a series of fixed and movable contacts, a circuit-controller for the movable contacts constructed to break certain circuits 5 and to establish certain other circuits, means normally tending to move said circuit-controller, restraining means therefor, and separate electromagnets included in the main and party lines to be energized to effect release of 10 the circuit-controller from the restraining device, substantially as specified.

3. In combination, main and party lines, a series of circuit-closers therefor comprising fixed and movable contacts, a circuit-controller 15 normally acted upon by a force and comprising differential lifts or cam portions to effect unequal movement of the shiftable contacts, means for normally holding the circuit-controller in restraint, and an electrically-controlled releasing mechanism to effect 20 liberation of said circuit-controller, substantially as specified.

4. In combination, main and party lines, circuit-closers therefor comprising fixed and 25 movable contacts, a circuit-controller normally acted upon by a force and having differential cam portions or lifts and provided

with corresponding stops, a detent coöperating with said stops to hold the circuit-controller in the predetermined position, and an 30 electrically-controlled releasing mechanism to effect liberation of said detent-lever to permit establishing of the circuits and a resetting of the several parts in one complete movement of said circuit-controller. 35

5. In combination, main and party lines, a multiple electromagnet included in one line, a separate electromagnet adapted to be included in either of the lines, a circuit-controlling mechanism for throwing the circuits into 40 and out of action, and a permanent magnet arranged between the members of the multiple electromagnet for polarizing the same to admit of selection being made when it is required to cut one of a series of circuits into 45 the main circuit.

In testimony whereof we affix our signatures in presence of two witnesses.
